J. A. BROGAN

ART OF FINISHING THE EDGES OF PERFORATIONS

Filed Nov. 26, 1919

Fig. 5.

INVENTOR.

James A. Brogan

UNITED STATES PATENT OFFICE.

JAMES A. BROGAN, OF LAWRENCE, MASSACHUSETTS, ASSIGNOR TO UNITED SHOE MACHINERY CORPORATION, OF PATERSON, NEW JERSEY, A CORPORATION OF NEW JERSEY.

ART OF FINISHING THE EDGES OF PERFORATIONS.

Application filed November 26, 1919. Serial No. 340,706.

To all whom it may concern:

Be it known that I, JAMES A. BROGAN, a citizen of the United States, residing at Lawrence, in the county of Essex and State 5 of Massachusetts, have invented certain Improvements in the Art of Finishing the Edges of Perforations, of which the following description, in connection with the accompanying drawings, is a specification, 10 like reference characters on the drawings indicating like parts in the several figures.

This invention relates to a method of making and finishing the edges of perforations and to the product of the method, and 15 15 is herein illustrated as embodied in a method of producing lacing holes in the uppers of boots and shoes and in the finished shoe parts.

In the manufacture of laced boots and 20 20 shoes it is customary to form rows of lacing holes in the front portions of the quarters to receive the laces. Commonly the quarters have attached to them one or more backing pieces such as a lining and a stay through 25 all of which the lacing holes pass. In order to finish the lacing holes so that their edges will have a satisfactory appearance as well as sufficient strength to withstand the strain of the laces; it is customary to make use of 30 eyelets which may extend entirely through the quarter and the backing including the lining and stay pieces, or may extend only part way through from either the concealed or the exposed side of the article.

35 The present invention contemplates doing away with eyelets entirely, although, when the invention is used in the manufacture of boots and shoes, so-called "blind eyelets" which do not extend through the quarter, 40 may be used as of old in connection with the present invention if desired.

In carrying out the present invention as applied to boots and shoes, a shrinking agent such as heat is applied around the lac- 45 ing hole in the leather quarter on that side of the quarter which is concealed in the finished shoe to harden the edge of the lac- ing hole and to improve the appearance of the hole as viewed from the exposed or dis- 50 play side. Conveniently the hole or perforation in a quarter is first centered with respect to a heated annular member the diameter of which is slightly greater than that of the

perforation, and then the heated member is brought into contact with the flesh side 55 of the leather around the perforation to shrink the leather on the flesh side and thereby cause the grain side to bend or curl toward the flesh side. This treatment hardens the edge of the perforation so as to 60 render it more effective in withstanding the strain of the laces and at the same time rounds the edge of the perforation on the display side and imparts to it an improved 65 appearance.

Referring now to the accompanying drawings,

Fig. 1 is an elevation of part of a perforating mechanism, the work being shown in section after having been perforated; 70

Fig. 2 is an elevation of part of a heat applying mechanism, the work being shown in section before having been operated upon by that mechanism;

Fig. 3 is an enlarged view, principally in elevation, showing the manner in which the heat is applied and its effect upon the work;

Fig. 4 is a section of the completed work, and

Fig. 5 is a perspective of a portion of 80 a quarter after the perforations have been made and their edges finished.

In the drawings the work is shown as a quarter 7 of a shoe having a backing which comprises a lining 9 and a stay 11. In the 85 manufacture of a shoe having these parts it is customary to skive and fold the front and top edges of two quarters, then to sew the back edges of the quarters together, then to fasten the lining and stay to the quarters 90 by one or more rows of stitches located near the front edges of the quarters, then to punch the lacing holes and then to insert eyelets in the holes. The procedure outlined above is often varied in different ways, 95 for example by using cement to attach the lining to the quarter before stitching on the stay, and it should therefore be understood that the particular parts referred to and the particular means for fastening them together have been shown merely for purposes of illustration.

In carrying out the method on a part of a shoe such as that shown in the drawings, the quarter, lining and stay are fastened together by a row of stitches 13 which is

spaced from the front folded edge of the quarter as shown in Figures 1 and 5. If desired, a certain amount of cement may be used instead of or in connection with the row 5 of stitches 13 but in any event the quarter and its backing, whatever that may be, are held in the proper superposed relation that they will occupy in the finished shoe so that the lacing holes may be properly made.

10 The parts thus fastened together and held in their proper superposed relation are next perforated for example as indicated in Fig. 1 wherein the bed of a perforating machine is indicated at 15 and the punch at 17, the 15 perforations extending through the quarter, lining and stay. The work is then turned over, a portion of the lining and stay bent back as shown in Fig. 2 and heat applied to the concealed side of the quarter about 20 the holes therein. Conveniently, a tool somewhat similar to a harness punch may be used, one jaw carrying a partly hollow heating member 19 maintained at a proper temperature by an electric heat unit 20 and 25 the other carrying a support 21 provided with a centering projection 23. The member 19 may have an annular operative lower end of slightly greater diameter than that of the hole in the leather quarter so that 30 when this member is brought down upon the concealed side of the quarter, which is usually the flesh side, the leather around the hole on that side is shrunk as indicated roughly in Fig. 3 so as to draw inwardly 35 the margin of the unheated side. The effect of this treatment is to harden the edge of the hole, to impart to it more or less of a funnel shape and to remove any fuzz or fibers in case the punching operation was 40 not a clean one.

After the holes in the quarter have been finished by the shrinking operation, which has just been described, those portions of the lining and stay, which have been bent 45 back to expose the concealed side of the quarter, are laid down again in their original positions and their front edges fastened to the front edge of the quarter for example by a row of stitches 25, this last operation 50 being conveniently performed by a sewing machine having an undertrimming attachment to trim the edges of the lining and stay so that the completed work in cross-section appears as shown in Fig. 4.

55 Having thus described my invention, what I claim as new and desire to secure by Letters Patent of the United States is:

1. That improvement in the art of finishing a perforation in a piece of material 60 which comprises applying simultaneously at all points around the perforation on one side of the material a shrinking agent to cause the edge of the perforation to curl from the opposite side toward the side to 65 which the shrinking agent is applied.

2. That improvement in the art of finishing the edge of a cylindrical perforation in a piece of material which consists in shrinking the material simultaneously at all points throughout a selected locality about one end 70 of the perforation to such an extent as to draw toward the shrunken locality the margin of the material located about the other end of the perforation and thereby impart to the other end substantially a funnel 75 shape.

3. That improvement in the art of finishing the edge of a perforation in a piece of material which comprises centering the perforation with respect to an annular heated 80 member having a diameter greater than that of the perforation and then applying the member to one side of the material around the perforation.

4. That improvement in the art of preparing a lacing hole in a piece of work composed of a piece of leather and a piece of backing which comprises fastening the leather and backing together in such manner as to leave one margin of each free and 85 at the same time hold the margins in proper superposed relation, making a lacing hole which extends through the free margins of both pieces, separating the margins, shrinking the leather about the hole in the leather 90 on that side of the leather which is next to the backing piece, bringing the margins back into their first relation with the holes in the backing and in the leather in alignment, and fastening the margins together 95 against further separation.

5. That improvement in the art of making boots and shoes which consists in perforating the quarter and backing parts while said quarter and parts are held in their proper 100 superposed relation, and then applying a shrinking agent to the concealed side of the quarter around the perforations therein to cause the edges of the perforations to curl from the exposed side of the quarter toward 105 the concealed side.

6. That improvement in the art of making boots and shoes which consists in perforating the quarter and backing parts while said quarter and parts are held in their 110 proper superposed relation, and then applying heat to the concealed side of the quarter around the perforations therein to cause the edges of the perforations to curl from the exposed side of the quarter toward the concealed side.

7. That improvement in the art of making boots and shoes which comprises fastening the quarters and lining together, punching them to form lacing holes, and then applying a shrinking agent to the concealed side of the quarters around the holes therein. 115

8. That improvement in the art of making boots and shoes which comprises fastening the quarters and lining together, punching 120

them to form lacing holes, and then applying a heated member to the concealed side of the quarters around the holes therein.

9. That improvement in the art of making boots and shoes which comprises fastening the quarter and lining together by a row of stitches which is spaced from the front edge of the quarter, making a row of perforations in the quarter and lining at a locality between the row of stitches and the front edge of the quarter, shrinking the material of the quarter in localities about the perforations on that side of the quarter which is next to the lining, and then fastening the edges of the quarter and lining together by a second row of stitches.

10. An article of manufacture comprising a display piece and a backing fastened together, there being a perforation extending through both pieces, the material of the dis-

play piece about the perforation being shrunken on that side of the display piece which is next to the backing.

11. An article of manufacture comprising a piece of leather and backing material therefor, there being a row of holes extending through the leather and backing, the leather around the holes therein being harder than the remaining portions of the leather.

12. That improvement in the art of finishing the edge of a perforation in a piece of material which consists in shrinking the material throughout a selected locality adjacent to the perforation to such an extent as to draw toward the shrunken locality the material in other localities about the perforation.

In testimony whereof I have signed my name to this specification.

JAMES A. BROGAN.
